UNITED STATES PATENT OFFICE.

TOM HARVEY, OF MIDDLETOWN, OHIO.

PAPER AND PULP MAKING CYLINDER MOLD.

Application filed August 23, 1927. Serial No. 214954.

My invention relates to the structure and operation of cylinder molds in paper and pulp making.

The cylinder mold in a paper making machine is the large screen surfaced drum or roll which revolves in the pulp vat and collects the pulp from the paper stock in this vat, which pulp is lifted from the mold by means of a felt band. The felt band passes over the mold and between it and a suction roll or couch roll, the suction of which aids in the lifting of the pulp from the mold and forces out a considerable quantity of water therefrom, as the felt passes around the roll.

15 The usual type of pulp vat is a rectangular tank having an inlet chamber separated from the mold chamber by a baffle. The paper making stock flows into the inlet chamber and over the baffle wall to the mold chamber. Here it must pass through the mold or around it in order to get to the drain resulting in the collection of the solid matter of the stock on the screen.

20 To the extent that the stock escapes around and beneath the mold, there is a waste of paper making materials, and also a pollution of streams into which the paper is drained, that makes trouble for the paper mill both from riparian owners and from the public 25 authorities.

In order to prevent this waste it is the practice to pack the space between the mold and the side walls of the vat by means of packing strip engaging around the ends of the mold, and fastened in this position. This packing 30 does not last, and cannot be maintained tight, and when it is made tight, the drums are hard to revolve, and cannot be revolved rapidly.

Also, where the felt is used to revolve the 35 cylinder molds, the strain on the felt is too great, when the packing is tight.

Another defect of the type of mold of the art lies in the fact that the stock tends to run or slip back down the cylinder wall as it revolves to bring the screened-out pulp up to the felt and couch roll, so that the delivery of stock to the felt is not as well formed as it should be, and is not always uniform.

Finally, the amount of water in the pulp 40 as it is formed on the screened surface of the cylinder mold is too great, or at least much greater than should be required, with the result of loss in heat and power in drying out the stock.

45 It is the object of my invention to provide

a cylinder mold which is closed at both ends. A hollow shaft forming a continuation of the cylinder acts as an outlet for the water which has passed into the cylinder mold, and is connected with a water circulating pump. This 50 shaft may be used for setting up a small vacuum within the cylinder. A connection from the hollow shaft is always made to the water circulating pump and in addition I may use an air vacuum pump to exhaust the air 55 within the cylinder mold. I am thus able to use a regular packed gland for the journals of the cylinder mold in the tank, and all of the water which escapes from the machine must pass through the screen of the cylinder mold. 60 I can revolve the mold with small power because the glands or stuffing boxes can easily be made water-tight without developing great friction, which is not the case when the mold itself is packed. The small amount of 65 suction which I am able to apply to the mold holds the pulp against slipping back on the mold and causes a thicker and more uniform body to be collected upon the mold at any given speed of revolution thereof. Strains 70 are taken off the felts, and the drainage water is free of pulp, since it will all have been thoroughly screened by the mold. I am enabled to make a better paper more rapidly 75 with less waste of materials, and with great 80 economy in power, and can exercise a complete control of the flow of stock, speed of the mold, and thickness of the sheet formed on the felt from the mold, and also am able to provide a pulp to the felt which is not as full 85 of water, as in the usual practice.

I illustrate in the drawings an embodiment of my invention, as an example of one way of applying the same, and will describe this embodiment in full, and set forth the novelty of 90 my invention in the appended claim.

In the drawings:—

Figure 1 is a side elevation of the machine.

Figure 2 is an end elevation taken at the left of Figure 1.

Figure 3 is a perspective of the one head 100 of the cylinder mold.

Figure 4 is a top plan view of the machine with the screen surface of the mold broken away.

Figure 5 is a detail section of the cylinder mold.

Figure 6 is a section on the line 6—6 of Figure 5.

The pulp vat, which is of usual shape, has 110

the pulp or stock inlet chamber 1, and the mold chamber 2, with the baffle wall 3 between the two chambers over which the stock flows. The felt is indicated at 4, and a couch or suction roll at 5. The arrows in Figure 2 indicate the direction of motion. Paper making machines may have a series of pulp vats, cylinder molds and couch rolls, dependent upon how many layers are to be built up in making the desired paper web.

The cylinder mold is formed with a surface of screening material, which is of the usual cylinder mold type, and I have not illustrated it in detail, but have indicated the screened surface at 6. Ordinarily it will be built up of closely interspaced rods with layers of wire fabric of increasingly small mesh stretched over the rods.

The screened surface is supported by a series of spiders which in the form selected have internal ring shaped portions or hubs 7, and horseshoe shaped spokes 8 on which the screen is arranged. These spiders are fixed firmly to a large central shaft 9, which has a series of holes 10 therein lying in the spaces between the spiders.

The one end of the central hollow shaft has a plug fitted therein (Fig. 3), which has a solid portion 11, spaced arms 12 which lie inside of the shaft in the space between the rows of holes lengthwise thereof, and which has a spindle or shaft portion 13, which extends out through the side wall of the vat. This shaft has a packing gland or stuffing box 14 to protect its outlet from the vat, and I have shown a journal 15 for this spindle, and a drive 16 for the cylinder mold applied to the said spindle.

At the other end 17 of the hollow shaft, it is extended without holes therein, out through the wall of the vat and its exit is protected by a gland or stuffing box 18. The end of the shaft portion is supported in a bearing 19, and terminates in an outlet box 20. The entrance of the shaft to the outlet box is protected by a gland 21, and the shaft is free to revolve in the outlet box. The outlet box has an outlet at 22 for air, and an outlet at 23 to a pump for removing the water, instead of permitting the water to drain off by gravity, as in usual constructions. I have not illustrated an air pump or a water pump, but have inscribed on the drawings the points where their conduits will be applied to my device.

The cylinder is provided at both ends with solid heads 24 and 25, which completely close the cylinder ends and shaft head 11 closes one end of the hollow central shaft. The other end of the cylinder is closed by connecting the outlet 23 with the water pump and the outlet 22 with the air pump. In operating

the device the water and pulp or stock is pumped into the vat whence it flows over the baffle into the mold chamber, the mold is driven around and a water pump is preferably applied to the one outlet while an air pump is preferably applied to the other outlet. The water and pulp cannot escape from the mold vat without passing through the screen and out through the holes in the central shaft, through the shaft to the outlet box, and thence to the pump or pumps. When suction is applied by means of the air pump, there is a small vacuum head on the mold. To be true that portion of the screen from the line of felt contact down to the top surface of the stock is free to admit air to supply the suction line, but there will be enough vacuum within the mold to tend to draw the stock more rapidly through the screen and hold a thicker layer of it on the mold wall as it rises from the level of the stock. By controlling the outlet pump the difference of level between the water inside of the mold and outside of the mold can be regulated, so as to keep it as near the lower level of the hollow shaft as is desired. The mold will revolve easily with the felt without any drive of its own, since there will be very little friction working against it. The mold screen does not permit an appreciable quantity of fibrous stock to pass through it and hence there will be no stream pollution.

I find in practice that I obtain a better sheet of paper, which is also produced with considerably greater economy by the use of my mechanism, than with the old mold mechanism now employed universally, and that I can control the various elements of thickness, speed, flow of stock, etc., so as to obtain an accuracy of control, in contradistinction to the practice of today, in which the mold operation is hit or miss, and largely dependent upon the skill of the operator. My felts last longer and the whole operation is more uniform and requires less supervision.

Having thus described my invention, what I claim as new and desire to secure by Letters Patent, is:—

In a paper making machine the combination of a pulp vat, a cylinder mold within the vat, said mold having closed ends, a hollow tubular axial support extending through said mold having suction apertures, said support having spiders fixedly mounted thereon supporting said mold, a plug in one end of said support having a drive shaft connected therewith, said support having its other end open, and means for connecting said open end with a water and air escape line.

TOM HARVEY.
